BOILER REPAIR DEVICE

Henry Eisenberg, Bronx, N. Y.

Application May 14, 1940, Serial No. 235,155

7 Claims. (Cl. 220—25)

The present invention relates to improvements in repair devices, and more particularly to an improved boiler repair plate.

When a boiler or a pipe springs a leak, there is usually present in the vicinity local to said leak a rotten area which rotten area is not only weak but usually the situs for other leaks. The present type of boiler repair plug covers only a small area and if there are a series of leaks present thereabout outside of this area more than one plug will be required and in many cases even when a plurality of plugs are used there are still unstopped leaks.

Therefore the main object of my invention is to provide a boiler repair plate which will cover a relatively large area.

Another object of my invention is to provide a boiler repair plate which will cover a relatively large area the same size plug being adaptable for use on boilers having different degrees of curvature.

Another object of my invention is to provide a boiler repair plate consisting of a gasket, a stiff backing for said gasket, and means for causing said backing to assume and hold the shape of the face of the boiler on which said repair plate is to be used.

Still another object of my invention is to provide a boiler repair plate which may be used to plug up relatively large holes.

Other objects of my invention will be set forth in the following description and drawing which illustrate preferred embodiments thereof, it being understood that the above statement of the objects of my invention is intended generally to explain the same without limiting it in any manner.

Figure 1 is a sectional view along line 1—1 of Figure 2;

Figure 2 is a top plan view of one embodiment of my device, shown partially broken away and secured to a boiler;

Figure 3 is a sectional view along line 3—3 of Figure 1;

Figure 4 is a side view of another embodiment of my invention secured to a boiler, shown partially in section; and

Figure 5 is a front view of the embodiment illustrated in Figure 1—3, showing my device unattached to a boiler.

Referring to the drawing, B designates a boiler having holes or leaks H formed therein.

Referring more particularly to Figures 5, my device consists primarily of a gasket 3, a backing 4, a former 5, and means 6 for retaining said

device to the defective area. The gasket 3 is formed of any suitable gasket material such as sheet rubber or cork, etc., and is generally of rectangular shape. Superimposed on said gasket 3 and of similar shape thereto, is the relatively stiff resilient backing member 4 which is preferably made of a metal or material having substantially the same resiliency and stiffness of light gauge spring steel. Passing through holes 10 and 8 concentrically formed in gasket 3 and backer 4 is the L-shaped bolt 9. While I have shown an L-shaped bolt, it is quite obvious any type of toggle bolt or similar device may be substituted therefor. A rubber washer 10, metal washer 11, and nut 12 are engaged by the bolt 9 and are positioned in the order mentioned over the backing member 4, the purpose of said members 10, 11 and 12 being merely to insure against leakage through apertures 7 and 8 formed in members 3 and 4.

Also engaged by the bolt 9 through the opening 13 is the forming member 5 made of any substantially rigid material such as cast iron, steel, etc. In the present embodiment I have shown the forming member 5 of semi-cylindrical shape having its two longitudinal edges 14 in contact with the top face of the backing plate 4, but it is obvious that said plate 4 may be of any suitable shape which will serve the same purpose. A nut 15 is engaged by the bolt 9 and is used for tightening down the former 5.

My device is applied to the defective area of a boiler as follows:

The horizontal arm 16 of the L-shaped bolt 9 is inserted through one of the leaks or holes H in the boiler B, the most appropriate and convenient hole being one which will readily receive the arm 16 and which is so positioned that the gasket member will completely cover any surrounding leaks. Thereafter the nut 12 is tightened, thus compressing the rubber washer 10 and the gasket 3 in the area below the washer 10 and causing the horizontal arm 16 to press against the inner face of the boiler B. In order to conveniently tighten the nut 12, the former 5 and the nut 15 may be removed so as to allow free access to said nut and thereafter replaced. The nut 15 is then tightened, forcing former plate 5 downwardly, the edges 14 thereof causing the backing 4 and the gasket 3 to assume the shape of the boiler and compressing the gasket 3 to said boiler. It should be noted that the edges 14 of the former 5 and the longitudinal axis of the gasket 3 and backing 4 run parallel to the straight line elements of the boiler B.

The embodiment illustrated in Figure 4 differs slightly from the aforescribed embodiment and consists of similar gasket 3', backing 4', washer 10' nut 17', former 5', nut 15' and bolt 9'. However, in this embodiment, a pair of tapped holes 17 are formed in the top of former plate 5' near the ends thereof, the threads of said holes 17 engaging the threads of a pair of set screws 18. The purpose of these set screws is to apply additional pressure to the backing 4' and the gasket 3', the additional pressure being applied after the nut 15' has been tightened.

I have shown preferred embodiments of my invention, but numerous alterations and omissions may be made without departing from its spirit. For example, I have shown a single retaining bolt member passing through the center of the former plate 5, but it is obvious that a pair of these may be positioned on each end of the former plate. Nor do I wish to be limited to the type of retaining device described, since other types may be substituted therefor and different shapes of forming plates may also be used.

While my device has been illustrated as applied to a cylindrically shaped boiler wall, it should be understood that the device may be applied to a wall of any shape or an absolutely flat wall. Although I have named my article a boiler repair device, it may be applied to numerous walls such as large pipes, boats, etc.

I wish it to be understood that wherever in the claims I mention or refer to a "forming plate" or "forming member" I wish this to include any means whose function is to shape the backing member to conform to the defective wall and to bear on said backing member.

I claim:

1. A device of the character described comprising a gasket member, a backing member superimposed on said gasket member, a former plate superimposed on said backing member, said former plate being concave and having only a pair of parallel edges in contact with said backing member, and means for retaining said device on a defective wall.

2. A device of the character described for use in plugging leaks in a defective boiler, said device comprising a gasket, a backing member superimposed on said gasket and a forming plate superimposed on said backing member, said forming plate having only a pair of parallel edges in contact with said backing member, axially concentric holes formed in said gasket, backing member and forming plate, a bolt passing through said holes said bolt having means at its lower end adapted to engage the inner face of the boiler, and a nut engaged by the free end of said bolt member.

3. A device of the character described for use

in plugging leaks in a defective boiler, said device comprising a gasket, a backing member superimposed on said gasket and a forming plate superimposed on said backing member, said forming plate being concave and having only a pair of parallel edges in contact with said backing member, axially concentric holes formed in said gasket backing member and forming plate, a bolt passing through said holes said bolt having means at its lower end adapted to engage the inner face of the boiler, and a nut engaged by the free end of said bolt member, said former plate having a plurality of threaded holes tapped therein, said holes having set screws engaged therein.

4. A device as claimed in claim 3, in which there are provided a rubber washer, a metal washer superimposed on said rubber washer, and a nut superimposed on said metal washer, said metal and rubber washers and said nut being engaged by the bolt between the backing member and the forming plate.

5. A device of the character described comprising a gasket, a pliable backing member superimposed on said gasket and similarly shaped thereto, a hollow semicylindrically shaped forming plate superimposed on said backing member, the longitudinal edges only of said plate being in contact with said backing member, means for forcing the edges of said forming plate against the upper face of the backing member, and means for retaining said device against a defective wall.

6. A device as claimed in claim 5 in which the gasket and backing member are of rectangular shape and in which the edges of the forming plate which come in contact with the backing member are parallel to the longitudinal axis of the gasket and said backing member.

7. A device of the character described for use in plugging leaks in a defective boiler; said device comprising a gasket, a backing member superimposed on said gasket and a forming plate superimposed on said backing member, said forming plate having only a pair of parallel edges in contact with said backing member, axially concentric holes formed in said gasket, backing member and forming plate, a bolt passing through said holes said bolt having means at its lower end adapted to engage the inner face of the boiler, and a nut engaged by the free end of said bolt member, a rubber washer, a metal washer superimposed on said rubber washer, and a nut superimposed on said metal washer, said metal and rubber washers and said nut being engaged by the bolt between the backing member and the forming plate.

HENRY EISENBERG.
